UNITED STATES PATENT OFFICE.

ALBERT TWIGG, OF GARRETT, PENNSYLVANIA.

COMPARTMENT PAIL.

Application filed May 2, 1922. Serial No. 557,948.

To all whom it may concern:

Be it known that I, ALBERT TWIGG, a citizen of the United States, residing at Garrett, in the county of Somerset and State of Pennsylvania, have invented certain new and useful Improvements in a Compartment Pail; and I do hereby declare the following to be a full, clear, and exact description of the invention, such as will enable others skilled in the art to which it appertains to make and use the same.

This invention relates to a dispensing pail or receptacle.

One object is to provide a novel article of this kind adapted to have compartments to hold a plurality of materials and each compartment having an individual closure, whereby a plurality of materials may be carried at the same time without admixture in order to avoid separate trips for each material between the source of supply and source of use, and for instance on a farm or around a stable, to carry corn, oats, wheat, etc.

Another object is to provide a construction having openings in its side walls through which the material discharges, the wall having intervening strips provided with guide strips on one side and division plates on the other side, all secured together preferably by fastening means common to them so as to produce an exceedingly rigid structure.

Still another object is to provide a construction in which the slides or closures and the strips are embraced by an adjustable band disposed intermediate fastening means thereof, in order to maintain the slides, the wall and the strips in frictional contact to the desired degree.

Additional objects and advantages will become apparent from a consideration of the description following taken in connection with accompanying drawings illustrating one practical embodiment.

In said drawings:—

Figure 1 is a side elevation;

Figure 2 is a fragmentary side elevation on an enlarged scale, showing one of the closures in raised or open position;

Figure 3 is a plan view of the pail with the cover removed;

Figure 4 is a horizontal cross sectional view on the line 4—4 of Figure 1; and

Figure 5 is a vertical sectional view on the line 5—5 of Figure 1.

Like reference characters designate like or corresponding parts in the different views.

Referring specifically to the drawings, 60 the pail has a cylindrical side wall at 10 and a bottom wall at 11. It is open at the upper end or top and has an inwardly extending flange 12 to removably receive a closure 13 provided with an upstanding 65 flange 14 to frictionally engage the inner edge of the flange 12.

The interior of the pail is sub-divided into compartments 15 in any suitable manner, for instance by means of partition 70 plates 16 riveted or otherwise secured together at the center of the pail as at 17 and the outer ends of which are provided with fastening flanges 18, riveted as at 19, soldered or otherwise secured to the wall 75 10. Walls 16 terminate below the flange 12 to provide clearance for the closure 13. The upper ends of the flanges 18 extend above the partition 16 proper and then inwardly so as to frictionally and yieldingly 80 engage the flange 14 as at fingers 20 to increase the security of the fastening of closure 13.

Wall 10 is cut away to provide openings 85 at 21, one leading from each compartment 15. Placed against the strips 22 which are provided as part of the wall 10 and intermediate the openings 21, are guide strips 23, through which the rivets 19 also pass in order to rigidify the strips 22 as well as 90 generally rigidify the structure.

Slidable vertically on the exterior of the wall 10 are a plurality of closure plates 24, arcuate as shown, one for each opening 21, and the side edges of which closure plates 24 are 95 disposed intermediate the guide strips 23 and the strips 22, to slidably mount the closure plates.

Loops 25 may be provided on the closure plates 24 to facilitate raising and lowering 100 them while the pail as a whole may have a bail 26 pivoted thereon to facilitate portage thereof.

It will be seen that the various commodities desired to be used in the pail may be appropriately placed in the compartments 15 and when the same is to be dispensed, the appropriate closure 24 is elevated to the desired extent. The pail forms a very handy article and effects a saving in labor especially where 105 a number of commodities are separately carried in a bucket, pail or the like from the

source of supply to the source of use. I have particularly found it useful about the farm or stable in carrying different feeding materials like corn, wheat, etc., enabling one trip 5 to be made as compared with a plurality of trips as is now the practice, from the source of supply to the source of use.

The closures 24 are maintained against accidental displacement by the binding action 10 or frictional engagement of the wall 10 and strips 23 with the closure plate. In order to increase this degree of frictional contact when desired and to reinforce the plate 24 against outward pressure, a band is provided 15 at 27, being disposed intermediate pivots 19 varying in heights of their location so that the band will not become displaced. This band is flexible and accordingly exerts pressure on the strips 23 by 20 contacting therewith adjacent their side edges and exert reinforcing pressure on the plates 24 approximately centrally of their side edges. The degree of pressure exerted by the band 27 may be varied through the adjustment of a buckle at 28 which may consist of a flexible element to be tied together at its ends and adapted for engagement with terminal hooks 29 on the band.

The various parts composing my device 30 are preferably constructed of a suitable sheet metal but of course it may be made from any material desired or preferred as will be obvious.

It will be understood that the pail may 35 also be used with liquids by rendering the compartments water tight in a suitable manner.

As merely one practical embodiment has been illustrated and described, it is to be understood that changes in the details may be 40

resorted to provided they fall within the spirit and scope of the invention.

I claim as my invention:—

1. A portable pail having partition means therein, the side wall of the pail having openings therethrough and strips intermediate the openings, guide strips disposed against said strips, securing means common to said partition means, first mentioned strips and guide strips, and closures slidable intermediate said guide strips and the first mentioned strips. 45

2. A portable pail having partitions therein provided with securing flanges, the side wall of the pail having openings therethrough and strips intermediate the openings, guide strips disposed against said strips, fastening elements passing through said flanges, first mentioned strips and guide strips, and slidable closures engageable intermediate the first mentioned strips and guide strips. 55

3. A portable pail having partitions therein provided with securing flanges, the side wall of the pail having openings therethrough and strips intermediate the openings, guide strips disposed against said strips, fastening elements passing through said flanges, first mentioned strips and guide strips, slidable closures engageable intermediate the first mentioned strips and guide strips, and a pressure band surrounding said guide strips and closures and disposed intermediate said fastening elements. 65

In testimony whereof I affix my signature 70 in presence of two witnesses.

ALBERT TWIGG.
